Filed Apr. 30, 1956, Ser. No. 581,796

Claims priority, application Germany June 25, 1952

8 Claims. (Cl. 144—186)

The present invention relates to a wood ripping device, and more particularly it relates to a wood ripping device adapted to be used in the manufacture of wood wool or excelsior.

The present application is a continuation-in-part of my copending application Serial No. 362,921, entitled "Wood Wool Scoring Tool," filed on June 19, 1953, and now abandoned.

The known devices for the production of wood wool or excelsior of predetermined width include knife assemblies which serve for scoring timber fed into a wood wool making machine. Subsequently the cutter of a wood planer removes the scored wood layer from the remainder of the timber. The width of the wood wool fibers is thereby controlled by the lateral distance of the cutting edges of the adjacent scoring knives in the knife assembly. The scoring knives have a length of approximately 200 mm. and are assembled adjacent to each other in a scoring knife box in which they are kept in position by means of pressure screws.

Irregularities in the timber fed into the wood wool making machine, such as knobs or also foreign matters, frequently cause premature wearing out of the cutting portions of individual scoring knives or of several scoring knives, thereby rendering the entire knife assembly useless. In such case it is necessary to remove individual knives from the assembly, to reground the cutting edges thereof and thereafter to reassemble all of the knives again so as to properly align all of the cutting edges thereof. This assembling or reassembling of the knives is a rather time-consuming operation due to the requirement of achieving practically perfect alignment of the cutting edges.

Furthermore, the regrounding of the long flat scoring knives unavoidably causes an undesirable heating of the cutting edges. Thereby the quality of the knife material and also the useful life span of the cutting edge are considerably impaired.

It is a further disadvantage of the above described device that the cutting edges of the scoring knives if viewed under the microscope are not smooth but actually have a rough surface. These rough surface portions of the cutting edge cause considerable friction during the scoring of the timber and consequently a considerable portion of the wood is wasted by being transformed into wood meal rather than wood wool.

It is therefore an object of the present invention to overcome the above described disadvantages of existing wood wool making devices.

It is a further object of the present invention to provide a wood ripping device which can be easily and quickly installed in a wood wool making machine.

It is another object of the present invention to provide a wood ripping device which can be produced at extremely low cost.

It is yet another object of the present invention to provide a light weight low cost wood ripping device

which may be entirely discarded upon wearing out of any of the wood ripping portions thereof.

It is yet another object of the present invention to provide a wood ripping device which will permit the production of wood wool without forming any appreciable amount of wood meal.

Other objects and advantages of the present invention will become apparent from a further reading of the description and the appended claims.

10 With these and other objects in view, the present invention mainly comprises in a ripping device, in combination, a band support, and a plurality of pointed elements carried by and extending transversely of the band support, the pointed elements all having pointed ends 15 extending laterally beyond a side edge of the band support and, when the latter is located in a plane, the pointed ends terminating in a straight line located in the plane.

According to the present invention the ripping device comprises pointed elements in the shape of needles which are carried by a band support preferably consisting of two superposed bands or foils made of suitable material such as paper, cardboard, textile fabrics, synthetic resins or metal and having the needles glued to or pressed into the band support, preferably between two superposed bands.

According to another preferred embodiment of the present invention the needle carrying band consists of a synthetic resin in which the needles are embedded. According to another preferred embodiment of the present invention, the band support consists of a narrow thin sheet metal magazine, i.e. of two narrow sheet metal strips with chambers formed between the two superposed strips, each chamber adapted to receive one of the needle-like pointed elements.

35 It is within the scope of the present invention to have the needles which are carried by the band support arranged in such a manner that the needles form a row with adjacent needles abutting on each other or to have spacing means arranged between adjacent needles. The stems of the needle-like pointed elements may be of any desired cross section, such as circular thereby forming a cylindrically shaped stem, or rectangular, preferably so as to have an elongated rectangular cross section.

40 The pointed elements may be arranged in the band support in such a manner that the pointed ends of the individual needle-shaped elements will all extend laterally beyond one of the side edges of the band support, or, the needles may also be so arranged that the pointed ends of adjacent needles extend laterally beyond opposite side edges respectively of the band support.

45 Accordingly, according to a preferred embodiment of the present invention, the ripping device comprises in combination a band support having two opposite side edges, a plurality of first pointed elements carried by and extending transversely of the band support, the first pointed elements all having pointed ends extending laterally beyond one of the side edges of the band support, and a plurality of second pointed elements carried by and extending transversely of the band support, the second pointed elements all having pointed ends extending laterally beyond the other of the side edges of the band support and, when the latter is located in a plane, the pointed ends of each of the pluralities of pointed elements, respectively, terminating in a straight line located in the plane, the first and second pointed elements each being identically shaped and arranged in alternating sequence on the band support.

70 The present invention also includes in a wood wool making machine a ripping device as described herein and means for holding the ripping device in the wood wool making machine in such a position that the pointed ends of the needle-like elements will come in contact with and

rip timber which is fed into the wood wool making machine. The holding means for holding the wood ripping device in the wood wool making machine may be a separate unit, or may also be integral with the remainder of the wood wool making machine.

Preferably, all of the needle-like pointed elements in the ripping device are of identical shape. While the present invention is not limited to flexible band supports, excellent results are achieved by making the band support of a somewhat flexible material.

Thus, according to the present invention, in place of the previously used scoring knives of about 200 mm. length which have to be reground from time to time, short needle-like pointed elements are employed which are combined to a needle band by being carried by a band support. The distance of the individual pointed ends of the needle-like elements is controlled by the thickness of the stem portion thereof and can be increased by arranging spacing means between adjacent needle-like elements. The spacing means preferably are shaped like the stems of the needle-like elements, however without the pointed end portions thereof and of shorter length.

Due to the smallness and light weight of the individual needles, and consequently of the entire ripping device of the present invention, the same can be easily manipulated and inserted into the wood wool making machine or removed therefrom without loss of time. The heavy boxes required for receiving the assemblies of long scoring knives which previously had to be employed are not required in connection with the ripping device of the present invention.

Not only are the individual needle-like pointed elements of the present invention of small size and weight, but it is also possible to produce the same at extremely low cost. Therefore, when one or more of the individual pointed ends show signs of wear and are no longer capable of adequately ripping the wood, the entire needle band can be quickly removed from the wood wool making machine and replaced by new needle band. Due to its low cost it is usually not worthwhile to recover individual needles from a partly worn needle band and the used up needle band is therefore frequently discarded.

The length of the band support and the number of pointed elements carried by the same will vary with the working width of the wood wool making machine and generally amounts to up to 400 mm. The present invention, however, is not limited to any specific lengths of the ripping device.

Only the pointed ends of the needle-like pointed elements come in contact with the wood which is to be transformed into wood wool, and consequently only the pointed ends perform the essential task of ripping the wood. The stem portion of the pointed elements is carried by the band support and serves only for adhering the needle-like element to the band support. Only a fraction of a millimeter of the pointed end of the needle-like element is eventually worn out by the wood with which it comes in contact. Therefore, in order to save material, it is preferred according to the present invention to use the shortest possible needle-like elements, the stem however must be of sufficient length to permit rigid positioning of the needle-like elements in or on the band support. Thus according to a preferred embodiment of the present invention needle-like elements having an overall length of about 15 mm. are used. It is an additional advantage of the ripping device of the present invention that one short needle usually weighing considerably less than 1 gram will perform the same function as one of the conventional scoring knives weighing approximately 30 grams.

The needle-like elements which form part of the ripping device according to the present invention can not only be very economically mass produced and require only very little material, but they can also be immediately used without any further grinding operation. Furthermore, the needles can be produced in the most

suitable hardness and quality which will not be impaired by any subsequent grinding of the pointed ends thereof, since such grinding operation which has to be performed on scoring knives, is not required in connection with the needle-like elements of the present invention. Consequently, the useful life span of the pointed ends of the device of the present invention by far exceeds the useful life span of scoring knives prior to their being reground.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a schematic, fragmentary, elevated view, partly in section, of an embodiment of the ripping device of the present invention;

Fig. 2 is a schematic, fragmentary, elevated view, partly in section, of another embodiment of the ripping device of the present invention;

Fig. 3 is a schematic, fragmentary, elevated view, partly in section, of still another embodiment of the ripping device of the present invention;

Fig. 4 is a schematic, fragmentary, elevated view, partly in section, of yet another embodiment of the ripping device of the present invention;

Fig. 5 is an enlarged elevated view partly in section, of another embodiment of the ripping device of the present invention;

Fig. 6 is an enlarged elevated view, partly in section of still another embodiment of the ripping device of the present invention;

Fig. 7 is an enlarged elevated view, partly in section, of yet another embodiment of the ripping device of the present invention;

Fig. 8 is an enlarged plane view, partly in section, of an embodiment of the ripping device of the present invention;

Fig. 9 is an enlarged plane view, partly in section, of another embodiment of the ripping device of the present invention;

Fig. 10 is a schematic perspective view of the ripping device in combination with a holding means therefor in accordance with the present invention; and

Fig. 11 is a schematic perspective view of the ripping device located in a holding means therefor which forms an integral portion of the entire ripping and cutting arrangement of a wood wool making machine according to the present invention.

Referring now to the drawings and particularly to Figs. 1 and 2, needle-like elements 3 are shown carried by two bands 1 and 2 of equal width, which bands must be flexible and allow partial embedding of the needle shank portions therein, thus the bands may either be made of paper, cardboard, textile fabrics, synthetic resins or metal. When bands made of organic material are used, an adhesive material is applied to the sides of the bands facing each other. This adhesive is used to adhere the individual needle-like elements to the band support formed by the two bands and also to adhere the two free ends of the two bands of the support to each other. When metal bands are used as band support, the needle-like elements may be pressed between the two metal bands with suitable tools or by hand. The width of bands 1 and 2 is less than the length of the needle-like elements, so that the pointed ends of the needle-like pointed elements 3 will extend transversely of the band support. In the illustrated embodiment, the blunt end of the needle-like elements also extend slightly transversely of the band support formed by bands 1 and 2. Thus for instance the entire length of the needle-like elements may be 15 mm. and the width of the bands forming the band support may correspondingly be about 10

mm. Needles 3, as shown in Fig. 1 are formed with a cylindrical stem terminating at one end in a conical pointed end. By arranging the individual needles 3 so that adjacent needles abut each other, the distance between adjacent pointed ends will be equal to the diameter of the stem of the individual needles. Thus for instance needles having a stem diameter of 2 mm. will then have pointed ends 2 mm. distant from each other.

As shown in Fig. 2, spacing means 4 may be arranged between adjacent needles 3. These spacing means 4 have preferably the same diameter and generally the same configuration as the stem portion of needles 3. Thus, in the arrangement shown in Fig. 2, the distance between adjacent pointed ends will be 4 mm. if needle stem and spacing means diameters are 2 mm.

Due to the conical configuration of the pointed ends of needles 3 which terminate in a sharp point, very little friction is caused between the pointed ends and the wood and consequently upon ripping wood with the ripping device illustrated in Figs. 1 and 2 only very little waste of wood material is caused.

In the embodiment of the present invention illustrated in Fig. 3, adjacent needle-like elements, such as those shown in Fig. 1, may be so arranged as to extend laterally alternatingly beyond opposite side edges of the band support, so that every second pointed element serves as a spacing means for two first pointed elements. The ripping device according to this embodiment of the present invention can be used for instance first with the first pointed element extending toward the wood which is to be processed and, after one or some of the pointed ends of the first pointed elements have been worn out, the entire ripping device may be turned about 180° so that then the second pointed elements will then extend toward the wood.

Referring now to the embodiment illustrated in Fig. 4, the individual needle-like pointed elements are provided with stems of elongated rectangular cross-section. Individual pointed elements 5 abut with the elongated side faces of the stem portions. In this way a ripping device of very great stability is obtained. The width of the wood wool fibers obtained with the device illustrated in Fig. 3 is equal to the shorter cross-sectional dimension of the stems of pointed elements 5, which may for instance be 1 mm. As shown in Fig. 5, pointed elements 6 having a stem portion of rectangular cross-section may be arranged in the band support in such a way that the smaller side faces of adjacent needle stems are in abutting position. Thereby the distance of adjacent pointed ends will be equal to the larger cross-sectional dimension of the stem portions, for instance equal to 2 mm.

It must be noted that according to the present invention all of the pointed ends of the needle-like elements which extend laterally beyond one side edge of the band support terminate in a straight line.

The needle-like pointed elements 7 shown in the ripping device illustrated in Fig. 6 are provided with a stem portion of elongated rectangular cross-section and a lancet-shaped pointed end portion. One of the side faces 8 of the stem portion extends further upwards towards the pointed end portion than the opposite side face 9. The pointed element illustrated in Fig. 6 shows increased static resistance against lateral pressure on the pointed terminal portion of the lancet-shaped pointed end.

The pointed elements 10 shown in Fig. 7 are provided with pointed ends in the form of a sharp, conically curved edge, which in the illustrated embodiment are of semi-circular cross-section in the direction of the largest cross-sectional dimension of the elongated rectangular stem.

Best results with the pointed elements illustrated in Figs. 6 and 7, are obtained when the same are arranged in the band support in such a manner that the larger side

faces of the stem portions of adjacent pointed elements abut.

Figure 8 shows pointed elements 3 embedded in a band support 20 formed of synthetic resin.

Figure 9 shows pointed elements 3 partially surrounded by two bands 21 and 22 of a band support made of sheet metal. Due to the application of pressure, the two metal bands 21 and 22 firmly grip portions of the stems of pointed elements 3, thereby forming a supporting seat for the same.

The holding means for the ripping device illustrated in Fig. 10 comprises gripping jaws 12 and 13 which are pressed against each other by means of pressure screws 14 and 15. The ripping device 16 is clamped between angle plate 17 and pressure plate 18. Replacement of the ripping device 16 can be easily accomplished by loosening of the pressure screws 14 and 15, removal of the band support with the pointed elements carried thereon together with angle plate 17 and pressure plate 18, and replacement of the entire arrangement with an angle plate and pressure plate between which a new ripping device 16 has been positioned. It is of course also within the scope of the present invention to clamp a plurality of ripping devices such as ripping device 16 in the holding means. Thereby, the pointed ends of successive ripping devices may be arranged in staggered position relative to each other, so that the width of the wood wool fibers is reduced to a fraction of the distance between adjacent pointed ends in one ripping device.

As shown in Fig. 11, the holding means for the wood ripping device may also be arranged integral with the cutting portion, including cutting knife 19 of the wood wool making machine.

It will be understood that each of the elements described above, or two or more together, may also find a useful application in other types of ripping devices differing from the types described above.

While the invention has been illustrated and described as embodied in a ripping device for producing wood wool, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. For use in an excelsior machine, a self-contained ripping device, comprising in combination, a flexible band support having an adhesive face; and a plurality of pointed needle elements adhesively attached to and permanently carried by said band support extending transversely thereof, said pointed needle elements all having pointed ends extending laterally beyond a side edge of said flexible band support and, when the latter is located in a plane, said pointed ends terminating in a straight line parallel to said plane.
2. For use in an excelsior machine, a self-contained ripping device, comprising in combination, a flexible band support having an adhesive face; and a plurality of identically shaped pointed needle elements adhesively attached to and permanently carried by said band support extending transversely thereof, said pointed elements all having pointed needle ends extending laterally beyond a side edge of said flexible band support and, when the latter is located in a plane, said pointed ends terminating in a straight line parallel to said plane.
3. For use in an excelsior machine, a self-contained rip-

ping device, comprising in combination, a flexible band support having an adhesive face, and having two opposite side edges; and a plurality of pointed needle elements adhesively attached to and permanently carried by said band support extending transversely thereof, said pointed needle elements all having pointed ends extending laterally beyond one of said side edges of said flexible band support and, when the latter is located in a plane, said pointed ends terminating in a straight line parallel to said plane.

4. For use in an excelsior machine, a self-contained ripping device, comprising in combination, a flexible band support having an adhesive face; and a plurality of abutting pointed needle elements adhesively attached to and permanently carried by said band support extending transversely thereof, said pointed needle elements all having pointed ends extending laterally beyond a side edge of said flexible band support and, when the latter is located in a plane, said pointed ends terminating in a straight line parallel to said plane.

5. For use in an excelsior machine, a self-contained ripping device, comprising in combination, a band support comprising two flexible bands superposed upon each other each band having an adhesive face and the adhesive faces of said two bands, respectively, facing each other; and a plurality of pointed needle elements adhesively attached to and permanently carried between said two bands and extending transversely of said flexible band support, said pointed needle elements all having pointed ends extending laterally beyond a side edge of said band support and, when the latter is located in a plane, said pointed ends terminating in a straight line parallel to said plane.

6. For use in an excelsior machine, a self-contained ripping device, comprising in combination, a flexible band support comprising two flexible bands superposed upon each other each band having an adhesive face and the adhesive faces of said two bands, respectively, facing each other and made of a material belonging to the group consisting of paper, cardboard, textile fabrics and synthetic resins; and a plurality of pointed needle elements made of

steel carried between said two flexible bands and extending transversely of said band support, said pointed needle elements all having pointed ends extending laterally beyond a side edge of said band support and, when the latter is located in a plane, said pointed ends terminating in a straight line parallel to said plane.

5 7. For use in an excelsior machine, a self-contained tipping device, comprising in combination, a flexible band support having an adhesive face; and a plurality of pointed needle elements located adjacent to each other adhesively attached to and permanently carried by said band support extending transversely thereof, said pointed needle elements all having pointed ends extending laterally beyond a side edge of said flexible band support and, when the latter is located in a plane, said pointed ends terminating in a straight line parallel to said plane.

10 8. For use in an excelsior machine, a self-contained ripping device, comprising in combination, a flexible band support having an adhesive face; and a plurality of pointed needle elements each including a stem of substantially rectangular elongated cross-section adhesively attached to and permanently carried by said band support extending transversely thereof, said pointed needle elements all having lancet-shaped pointed ends extending laterally beyond a side edge of said flexible band support and, when the latter is located in a plane, said pointed ends terminating in a straight line parallel to said plane.
